SATURABLE CORE REACTOR SYSTEM

Uno Lamm, Ludvika, Sweden, assignor to Allmanna Svenska Elektriska Aktiebolaget, Västerås, Sweden, a corporation of Sweden

Application September 20, 1952, Serial No. 310,712

Claims priority, application Sweden September 22, 1951

5 Claims. (Cl. 323—89)

The object of the present invention is to provide an improvement of a transductor (i. e. a presaturated reactor) to obtain a remaining alteration of a quantity controlled by a temporarily acting control current.

Transductors as well as electron-tubes belong to a type of control apparatus in which the output quantity follows the variations of the input quantity and thus returns to some fixed value when the input quantity disappears. When transductors have previously been used in cases when it is desired to obtain an output quantity following an adjustable input quantity but remaining when the latter has disappeared, it has generally been necessary to make use of a device comprising mechanically controlled members such as for instance mechanically driven potentiometers.

A device of the last mentioned type may for instance be used to maintain a setting of the current in a lead to alternate this current at certain moments only by aid of electrical impulses.

The described device may also be used to maintain a test value, for instance the maximum value of a varying quantity, or to maintain a test value obtained at a moment when the quantity to be measured disappears.

The desired result according to the invention is obtained by using a transductor of which the outstanding feature is that the part of the transductor core which is arranged to be traversed substantially only by a direct current flux is at least partly made of a material having appreciable hysteresis. This involves the considerable advantage that the transductor which is a static apparatus without movable parts and without wear may be utilized for control devices of the described type.

In the accompanying drawing Fig. 1 schematically shows a suitable transductor core with windings according to the invention. Fig. 2 shows a diagram of the load voltage as a function of the control current of a transductor having such a core. In Fig. 3 a diagram of connections is shown illustrating a form of the invention.

According to Fig. 1 the single-phase transductor illustrated consists of a three-legged core 1 provided with alternating current windings 2 and 3 arranged on the outer legs. A part 4 of the length of the central leg, which at such a core may be substantially free from alternating current flux by proper arrangements of the alternating current windings, is made of a material having a hysteresis loop of considerable width and of a rectangular form as possible. This is attained if the said part 4 for instance consists of magnetic steel. According to the figure, the central leg is provided with two direct current control windings 5 and 6, one of which may suitably be a winding for self-excitation of the transductor. It is not necessary that the whole length of the central leg is made of magnetic steel, and if desired it may be provided with further control windings. The latter must not, however, be arranged on the central leg, the same result may be obtained by arranging them on the outer legs, and winding them in proper direction.

2

Fig. 2 shows the wide hysteresis loop of a transductor in a diagram of load voltage E as a function of the totally applied control current i_2 . This loop may be called the control curve of the transductor. The form of the control curve will be highly depending on the properties of the iron in the part of the transductor which is not subject to an alternating current flux, for instance the central leg of a transductor according to Fig. 1. If this part of the core is made of a material with high remanence and high coercive force, the control curve will also obtain a form which is determined by the hysteresis loop of the material in the leg which is free from alternating current flux. If according to Fig. 2 the transductor is controlled by the currents $i_1 + i_2$ along the curve A to the point B, and the control current is then decreased, the load voltage will fall along the curve C. If the transductor is premagnetized by a constant current i_1 it is thus possible to control the transductor within a comparatively large range by means of a relatively small control current i_2 . If a control current i_2 after having given the operating point B of the ascending curve branch A is diminished to zero, the load voltage will only fall to the point D of the only slightly sloping curve branch C. The voltage will thus only be subject to an insignificant decrease, and this decrease may be kept at a low value if the transductor has been so dimensioned that the remanent flux of the magnetic steel part in the leg which is free from alternating current flux can develop a.m. m. f. which is able to replace the control ampereturns from the current i_2 when this disappears.

A connection diagram for a transductor according to the invention is shown in Fig. 3. The two alternating current windings 2 and 3 on the core 1 are in series with self-magnetization rectifiers 7, 8 connected in parallel in an alternating current circuit connected to terminals 9, 10 and further comprising a full wave rectifier 11 and a load 12. It is already known that the transductor may be self-magnetized in such a way that it will operate in an unstable way, but in the present case it is desired that the transductor is provided with a self-magnetization which is as complete as possible to maintain the stability. If this desire is fulfilled only a few numbers of ampereturns are necessary to maintain the output voltage. In order to attain this result, a direct current is drawn from the rectifier 11 which may traverse a winding 5 which is arranged on the central leg. It is understood, however, that even other ways are available to increase the degree of self-magnetization, for instance by arranging winding parts 50 on the legs provided with alternating current windings so that each part is traversed by the rectified portions of the current in the alternating current winding on the opposite outer leg.

A direct current supplied from the terminals 14 is arranged to traverse a control winding 13 on the central leg or alternatively on the outer leg. This direct current serves as a premagnetization current like the current i_1 in Fig. 2.

The control current i_2 (Fig. 2) may be applied to the transductor by aid of a winding 6. For controlling the transductor this winding may be fed via an adjustable resistor which is suitably so connected that positive as well as negative control current may be obtained. It is also possible to alter the transductor output continuously by supplying the winding 6 with a current of suitable direction and duration which is applied in one or the other direction during shorter or longer time. In this case it is suitable to include time-delay means in the control circuit, for example a capacitor 15 and a resistor 16 and to arrange it so that different poles of the control current source 17 may be connected by means of one of two contacts 18 and 19. By closing the contact 18, the winding

6 will obtain a positive current according to Fig. 2, and by instead closing the contact 19 a so large negative current may be admitted as is necessary for the demagnetization so that the operating point F on the curve branch A in Fig. 2 will be reached again after this contact has been broken.

By suitable dimensioning of the transductor and its auxiliary means according to Fig. 3 it will be possible to obtain a voltage across the load which is increased from an initially low value by closing the contact 18 which suitably should be designed with a pressure contact. The increase of voltage will then be made dependent on the time during which the button is pressed, and owing to the delay circuit it will be possible to magnetize the transductor in dependence of the time during which the button is pressed. When the button is released, the transductor will maintain an output voltage, i. e. a voltage across the load which is unchanged except for the previously mentioned relatively insignificant decrease. To diminish the output voltage the button 19 is pressed during a time which corresponds to the desired decrease of voltage.

In order to improve such a pressure button setting, the transductor or its auxiliary circuits may be provided with other delaying members by which the resetting will be slower, and by which the transductor may be controlled with a higher precision. Such delaying members may consist of a capacitor or an inductance in the control circuit, self-magnetized circuit or output circuit arranged in any way known per se. They may also consist of thermic devices, for instances thermistors. In the latter cases, the controlling of the transductor may not only be performed by pressure buttons or such members but also in other ways. A transductor of the described type may be controlled to give an output quantity which is dependent either on the duration or on the product of the duration and magnitude of a current or a voltage applied to the input side of the transductor.

I claim as my invention:

1. A transductor device comprising a multilegged core structure having windings for alternating and direct currents, respectively, means for energizing said windings, a load in circuit with said alternating current windings, means whereby said last mentioned windings are arranged to give two interlinked magnetic circuits, said core having

one common core leg free from alternating current flux, and said direct current windings being arranged to give a direct current flux in said common core leg, at least part of the length of said common core leg consisting of a magnetic material having an appreciably larger hysteresis than the rest of the core, and control means in circuit with at least one of said direct current windings, the control action of said last mentioned winding being operative on the ascending part of the hysteresis loop of the transductor curve.

10 2. A transductor device according to claim 1, comprising a threelegged core structure, alternating current windings on the outer legs of the core, direct current windings on the central leg, at least part of the length of the central leg consisting of a magnetic material having an appreciably larger hysteresis than the rest of the core.

15 3. A transductor device according to claim 1, comprising a threelegged core structure, alternating current windings on the outer legs of the core, direct current windings on the outer legs of the core, said direct current windings being so arranged and connected as to give rise to co-operating magnetic fields in the central leg of the core, at least part of the length of said central leg consisting of a magnetic material having an appreciably larger hysteresis than the rest of the core.

20 4. A transductor device according to claim 1, comprising means for self-magnetization of the transductor.

25 5. A transductor device according to claim 1, comprising a number of direct current windings, one of which being arranged to pre-magnetize the transductor to a certain basic point, and another of which being adapted to receive a temporarily acting control current of a certain polarity, and a capacitor-resistor combination serving as a time-delay device in circuit with said last-mentioned winding.
